UNITED STATES PATENT OFFICE.

GEORGE R. ELLIOTT, OF DETROIT, MICHIGAN.

SECTIONAL CONCRETE BLOCK.

Application filed January 5, 1918. Serial No. 210,433.

To all whom it may concern:

Be it known that I, GEORGE R. ELLIOTT, a citizen of the United States of America, residing at Detroit, in the county of Wayne 5 and State of Michigan, have invented certain new and useful Improvements in Sectional Concrete Blocks, of which the following is a specification, reference being had therein to the accompanying drawings.

10 This invention relates to sectional concrete blocks and refers more particularly to a construction built up of blocks to form a hollow square or the like which can be advantageously used in the floor and ceiling 15 constructions of buildings, although in its broader aspects the invention is not limited to the particular use mentioned.

Among the objects of the invention are to provide a sectional block built of concrete 20 or the like which can be employed so as to do away with the use of wooden forms in building constructions; to provide a construction which, while sufficiently light in weight, will have the material so distributed 25 as to provide sufficient strength for load-supporting purposes; to so construct and arrange the parts that the lower surface of the blocks will form a substantially smooth and continuous plastering surface where it 30 is desired to use such surface as the ceiling, to provide a construction wherein the blocks go together without nails or other fastening devices; to provide a construction in which the blocks are so formed that they 35 can be economically molded and "pulled;" and in general to provide a new and improved construction of the character above referred to.

In the drawings:

40 Figure 1 is a top plan view showing one manner of using blocks embodying my invention;

Figure 2 is an enlarged side elevational view of one of the blocks;

45 Figure 3 is an enlarged view of the block partly in end elevation and partly in cross-section, the section being taken on the line 3-3 of Figure 2.

Figure 4 is a view similar to Figure 2 50 showing a slightly modified construction;

Figure 5 is a view showing a still further modification.

Describing in detail the particular embodiment of my invention shown in the 55 drawings and referring first to the general plan view, A A' A'', etc., designate a series

of blocks which at one end rest upon the girder B supported by the permanent supports C C'. These blocks have their opposite ends supported upon either a temporary or permanent support D and are spaced from each other to provide a space E in which there is poured concrete or the like so as to permanently fasten the blocks together. The blocks can be of any width and 60 length within the strength limits of the material, the block shown in the drawings being of a proportion of about one foot in width and about seven feet in length, although the dimensions can be varied to suit 65 the requirements of the work. Each of the blocks A A', etc. is formed of a plurality of sections F F' F'' F'', the end sections F and F'' being interlocked with the top and bottom sections F' and F'' respectively. The 70 particular construction and arrangement of the interlock for these blocks forms one of the main features of my invention.

In detail the end sections F and F'' have 75 their outer faces centrally beveled out at G' to provide a space in which the concrete E can be poured so as to securely fasten the end block F with relation to the next adjacent end block F''. At the top the end blocks are provided with a projecting flange portion H which is beveled at H' while at the lower end the end block is provided with a similar flange I which is beveled at I'. These flanges extend but a portion of the width of the main body 80 portion G of the end blocks, as shown in dotted lines in Figure 3, and the flanges H and I rest in seats J formed in the end portions of the top and bottom sections F' and F''. Each of the latter sections have 85 flanges K at each side which adjacent their ends are formed with projections K' to abut 90 interiorly against the end sections and resist any inward movement thereof. The top and bottom sections are also formed with a 95 hollowed out central portion giving a relatively light wall or main body portion, at the opposite sides of which there extends strengthening flanges K forming in effect a beam-floor system. The depth of the 100 strengthening flanges K is preferably proportioned to about one inch in depth for every foot in length of the block, although these proportions can of course be varied according to the load to be carried or supported. 110

It will be noticed that the flanges H and I

are provided with beveled surfaces which abut against corresponding beveled surfaces in the top and bottom sections. This not only facilitates the manufacture of the blocks but 5 also the assembly and when put together as shown in Figure 2 each section will be rigidly interlocked with its cooperating sections.

The assembled blocks after being arranged 10 in place as shown in Figure 1 then have concrete poured in the spaces E which will also flow into the recesses G' and when set will interlock the various blocks together into one permanent construction. In pouring the 15 concrete a temporary support or block N may be positioned at the lower end of the space E or I may employ the construction shown in Figure 4. In this construction the bottom sections F³ are provided with projections 20 O which meet at O' with a corresponding projection on the next adjacent block. Also if desired a steel I-beam or other supporting member P may be positioned in the space E and the blocks supported therefrom 25 by suspension means such as the wire or supporting members Q which are connected to eyelets R and R' cast into the lower sections of the blocks. Various changes in such details of construction can, however, be made 30 within the scope of my invention.

It will be noticed that where my sectional blocks are employed for a floor construction that the lower edges of the blocks form a substantially continuous and smooth plastering 35 surface, thus doing away with the necessity of supporting metal lath or the like from the lower surface of the floor supports. Moreover the trussing effect of the blocks is such that they can be employed as the load- 40 supporting means in contradistinction to previous constructions wherein the blocks simply served as forms around which the concrete was poured to form the load-supporting member.

45 In the construction shown in Figure 4 the lower surface can be used as a paneled ceiling in factory construction without plastering.

In the construction shown in Figure 5 I 50 have illustrated a structure which can be employed for roofs or the like in which the lower member of the hollow block can be omitted. In this construction the top sections T and T' interlock with the end sections 55 U and U', while at their lower ends the latter interlock with a joint bottom section V. The construction of the joint is similar to that described in connection with Figures 1 to 4, except that the top sections and the 60 bottom joint section are provided with ribs or flanges W which prevent the end blocks from moving inward. This last-mentioned construction is particularly adapted for fire-proofing steel construction.

65 While I have shown and described certain

constructions and uses of my invention, it is not limited to the particular forms and uses shown, as it could also be used for culverts and various other purposes. Also where used in building construction it is particularly advantageous, in that the hollow blocks themselves form a structure that can be used as a pipe trench and any part of the construction is removable. Also the hollow blocks could be used as a pipe trench or other conduit without reference to their other use. 70

What I claim as my invention is:—

1. A sectional block formed of concrete or the like comprising top and bottom sections having a relatively light main body portion and side flanges provided with projections near the ends thereof, of end sections adapted to fit against said projections and having projecting flanges fitting into recesses in the top and bottom sections. 80

2. A sectional block formed of concrete or the like comprising top and bottom sections having a relatively light main body portion and side flanges provided with projections near the ends thereof, of end sections adapted to fit against said projections and having projecting flanges fitting into recesses in the top and bottom sections, said end sections having a recessed central portion adapted in the assembled position of the parts to receive concrete or the like which when set will lock the sections together. 90

3. A sectional block formed of concrete or the like, comprising top and bottom sections each having a main body portion 100 formed with flanges at the respective edges thereof, said flanges and body portion being respectively formed with projections at each end of the sections, and end sections engageable at top and bottom between the projections formed upon the flange and body portion of the top and bottom sections. 105

4. In a sectional block of concrete or the like, a top plate having parallel depending flanges at opposite side edges thereof, end members transverse to said flanges supporting said top plate and bearing against shoulders formed transversely upon said flanges. 110

5. In a sectional block of concrete or the like, a top plate having parallel depending flanges at opposite side edges thereof and formed with depending projections adjacent its ends, and end sections supporting said top section engaged between shoulders formed upon said flanges and said depending projections. 115

6. A sectional block formed of concrete or the like, comprising top and bottom sections having a relatively light main body portion and flanges adjacent the side edges 125 thereof, and end sections engageable between said top and bottom sections adapted to bear against said flanges and provided with projections engaging recesses in the top and bottom sections. 130

7. A sectional block formed of concrete or the like, comprising top and bottom sections having a relatively light main body portion and flanges adjacent their side edges, 5 of end sections engageable between said top and bottom sections and adapted to bear against said flanges, said end sections having their central portions recessed to receive concrete or the like for locking adjacent 10 blocks together.

8. A sectional block of concrete, or the like, comprising top and bottom plates having parallel flanges adjacent side edges thereof projecting toward each other and 15 end members supported upon the bottom

plate and supporting a top plate and bearing against shoulders formed transversely upon said flanges.

9. A sectional block of concrete or the like, comprising a top and bottom plate, one 20 of which is provided adjacent opposite edges thereof with flanges projecting toward the other, said flanges being formed with shoulders adjacent their extremities and end sections interposed between said top and bottom plates and engaged between said shoulders. 25

In testimony whereof I affix my signature.

GEORGE R. ELLIOTT.
